UNITED STATES PATENT OFFICE

WALTER EASTER HASKIN, OF FLUSHING, NEW YORK, ASSIGNOR TO PRESSED & WELDED STEEL PRODUCTS COMPANY, INC., OF NEW YORK, N. Y., A CORPORATION OF NEW YORK

BOOKRACK

Application filed June 12, 1930. Serial No. 460,718.

This invention relates to a bookrack, and it is to be understood that in employing the title "bookrack" it is used in its broadest sense to include a book cabinet, book casing 5 or other suitable mount for a plurality of pivotally supported book holders, adapted to hold or support any type of book, which are counterbalanced and adapted to be moved from closed position to open position and 10 vice versa, without any banging or shocking to the holders and the books.

An object of the invention is to provide 15 an improved mounting for a series of books, which normally supports the books in closed position, but enables any or all of the books to be swung from a closed to open position for ready use.

My invention is particularly adapted for 20 use in connection with entry books such, for example, as loose-leaf books or binders in which entries can be easily and quickly made, and reference to the accounts or other data in the books can be quickly found.

Structurally, the invention embodies an 25 improved cabinet or casing for the book holders and books, improved means for closing the cabinet, improved counterbalancing means for the book holders and books, and improved means for removably coupling the 30 books to the book holders, all of which will be more fully hereinafter described and pointed out in the claims.

In the accompanying drawings—

Figure 1 is a perspective view of my improved bookrack, the view being taken looking at one corner of the device, showing more 35 specifically one end, the front and the top of the device, illustrating all of the books and book holders in closed position, but 40 ready for manipulation;

Figure 2 is a view similar to Figure 1, showing one of the books in open position;

Figure 3 is a view similar to Figures 1 and 45 2, showing all of the books in open position;

Figure 4 is a perspective view looking mainly at the rear of the bookrack, showing all of the books in closed position and the book closure in its lowered position, so that the book holders and books may be manipulated;

Figure 5 is a view in vertical, cross section through the bookrack, with the books in closed position and the book closure in its closed position, preventing movement of the books;

Figure 6 is a broken view in section on the line 6—6 of Figure 5;

Figure 7 is a view similar to Figure 5, but showing one of the book holders and books in open position and the book closure in its lowered position, out of the way of the movable book holders and books, all but one of the book holders and books being omitted for clearness.

Figure 8 is a view similar to Figure 7, showing one of the book holders and books in partially open position, or, in other words, in the position which the book holder and book take in their movement from open to closed position, and vice versa;

Figure 9 is a broken view mainly in plan, showing one book holder and book in partially open position, showing the other book holders with the books removed, and portions broken away and in section with illustrated details of construction; and

Figure 10 is an enlarged fragmentary view in longitudinal section through one of the book holders, illustrating more specifically the manner of securing a book.

My improved bookrack embodies a cabinet or case A, a series of book holders B pivotally mounted in the upper portion of the cabinet or casing A, and a series of books C removably connected to the book holders but having a novel arrangement of mounting and counterbalancing means.

In referring to the part A as a cabinet or casing, it is to be distinctly understood that the invention is not limited to any form or shape of this cabinet, as this may be varied to suit the trade, but a specific form is illustrated which is well adapted for the purpose.

The books C may constitute any type of book, including loose-leaf binders, and the construction illustrated and described in this application is particularly adapted for use in connection with entry books, so that entries may be easily and conveniently made and reference thereto conveniently had at all

times without any possibility of misplacing the book, and dispensing with the handling of books which are often heavy and cumbersome.

5 Referring to the cabinet or casing A, this may be made of sheet metal or any other suitable material, and comprises ends 1—1 connected by front and back members 2 and 3, respectively. The back member or wall 10 is preferably vertical and straight, and extends upwardly from the bottom of the rack for a portion of the length or height of the rack, and the front member or wall 2 is preferably set back from the front edges of the ends 1—1; the lower portion of this front wall is vertical, while the upper portion 2' thereof tapers forwardly to the front of the cabinet, thus providing sufficient leg room for an operator in a sitting posture to manipulate 15 the books and make entries therein.

The top of the cabinet is mainly open, but has what constitute end-pieces 4—4 connected by a front angularly-shaped flange 5 upon which the books may temporarily rest during 25 the time of uncoupled relation to the book holder, and while pages or sections of pages are being inserted or removed from the books.

The cabinet is preferably supported on rollers or casters 6 to facilitate its removal 30 from place to place, and the top portion 4 is shown at a slight angle, which is a convenient angle for positioning the book holders and books so that entries or reference can be conveniently made to the books while the operator is in a sitting posture, although, of course, it is distinctly understood that the angle of disposition of the book holders and books may be varied as desired.

All of the book holders B are of generally 40 oblong, hollow, box-like form to give sufficient body thereto, so that pivotal mountings in and connections with the book holders can provide the desired leverage for movement and counterbalance.

45 All of the book holders B are pivotally supported on a rod 7, which extends longitudinally through the upper portion of the cabinet and through all the book holders, the pivotal connection between the book holders 50 and the rod being slightly nearer one end of the book holders than the other, so that the preponderance of weight of the book holder and book is at one end, preferably the upper or rear end, to insure a complete opening and 55 closing movement due to gravity as the parts reach the extremes of their movement.

Suitable spacing sleeves 8 are provided 60 on the rod 7 between the book holders to properly space the latter, and said rod may be removably secured in the cabinet in any approved manner to permit of the ready assemblage of the parts and the removal and replacement of the parts as occasion may require.

65 The counterbalancing means for all book

holders and books are precisely alike, and hence the description hereinafter given of one set of counterbalancing means will apply alike to all.

A depending link 9 is pivotally connected 70 at its upper end to one side of the book holder B, as clearly shown at 10. This pivotal connection 10 is above the rod 7 when the book holder is in closed position, and a recess 11 is provided in the link 9 to accommodate the 75 rod 7 and the spacing sleeve 8, reference being particularly made to Figures 5, 7 and 8 of the drawings. The pivotal connection 10 is preferably located above and slightly beyond or "over center" of a line perpendicular 80 to the back of the holder B and passing through the center of rod 7 so that the force exerted by a spring 17 through link 9 would tend to hold the book more firmly in its closed position. The lower end of the link 9 is 85 pivotally connected, as shown at 12, to a lever 13, the pivotal connection 12 being intermediate the ends of the lever 13, said lever being pivotally supported on a rod or other suitable device 14, mounted on a bracket 15 90 fixed to the back wall 3 of the cabinet A.

The lever 13 is shown as a channel and carries at one end a pivoted arm 16, which is connected by the coiled spring 17 to a bracket 18 fixed to the rear wall 3 of the cabinet. 95 To adjust the tension of this spring 17 the arm 16 is formed intermediate its ends with a nut 19, which may have swivelled connection to the arm 16, and an adjusting screw or rod 20 extends longitudinally of the lever 13 100 to engage the swivelled nut 19 on the arm 16 and has rotary mounting in the pivoted end of the lever 13. A winged head 21 is fixed to one end of the screw-threaded rod 20 so that by manually turning this rod the arm 105 16 may be pivoted to vary or adjust the tension of the spring 17.

22 represents a second link located on the opposite side of the book holder to which the link 9 is connected, and this link 22 has a 110 pivotal connection 23 with the book holder B, such pivotal connection (when the book holder is in closed position) being in advance or forward of the rod 7 a proper distance for the function desired.

The lower end of the link 22 is pivotally connected to a triangular plate 24, this plate being pivotally connected to the bolt or rod 14 above referred to, and also pivotally connected to a plunger rod 25 of a dash pot 26. 120 The dash pot 26 has a pivotal connection 27 with a bar 28 fixed to the inner face of the front wall 2 of the cabinet. This pivotal connection 23 is preferably in a line passing through the center of rod 7 and parallel with the back of the holder B and spaced sufficiently from rod 7 to give the desired stroke or thrust to the plunger rod of the dash pot. It is to be further noted that the pivotal connection between link 22 and bell crank 24 should 125 130

lie in a line perpendicular to the back of holder B and passing through the center of rod 7. The said pivotal connection will then be seen to travel the same arc and return to the same point in either operation of opening or closing the book—the stroke of the plunger of the dash pot being identical in both operations.

In describing the linkage of the cushioning means I have described the exact structure illustrated in the drawings, but it is apparent that the plate 24 in reality constitutes a bell crank lever in its function and operation, and in the description hereinafter given of the operation of these parts the dash pot will be referred to as a whole by the reference character 26, and the other parts in more or less general terms as it is not the intention of applicant to be limited to the exact form of the parts shown in the drawings, as this is capable of considerable modification.

At the back of the cabinet a closure 29 is provided to cover the rear ends of the books when in closed position, and also functions to hold them in this position. The closure 29 is counterbalanced by what is generally known in the trade as a Pullman sash balance D, which has a spring operating means for balancing the weight of the closure and assisting in elevating the same, this balance being clearly illustrated in Figure 5 of the drawings.

This closure 29 preferably constitutes a cover in two sections, hingedly connected, as shown at 30, and both sections capable of vertical sliding movement in guides 31 adjacent the side walls of the cabinet and at the back thereof. This closure or cover 29 may have any suitable sliding coupled relation to the cabinet, but from the drawings this sliding coupling is indicated as an inwardly projecting flange 32 at each side edge of the closure 29, riding in a groove 33 at the back of the cabinet. To insure an easy and proper movement of the closure, racks 34 are fixed to the back of the cabinet, and pinions 35 supported on a shaft 36 mounted in the closure 29 ride freely on the racks.

When the device is in use the closure is in its lowered position, and when not in use or when the day's work is ended the closure is drawn upwardly and the upper section thereof is swung forwardly, as clearly indicated in Figure 5, and may be locked in this position as desired.

I have illustrated means for holding or locking the closure, which includes an overlying angular lip 37 at the upper end of the closure, which rests upon the parts 4 of the cabinet top, and also upon the book holders, and within this flanged lip I provide a latch or lock 38, indicated more or less diagrammatically in Figure 5 of the drawings, which operatively engages the perforated lugs 39 in the end walls 1 of the cabinet.

In Figures 9 and 10 of the drawings, I illustrate the preferred manner of coupling the books to the book holders. The book holders have inwardly projecting fixed lips 40 at one end, and movable inwardly projecting lips 41 at their other ends, for engagement with the backs 42 of the books C. The movable lips 41 constitute parts of the angle plates 43, mounted to slide within the hollow book holders B and controlled by latch arms 44, which also project into the book holders and have reduced fingers 45 at their inner ends projecting through openings 46 in the angle plates 43 and have a certain pivotal movement of the latch arms. The forward ends of these latch arms have finger grips 47 thereon.

The book holders have inwardly projecting flanges B', as clearly shown in Figure 10. The horizontal portions of the angle plates 43 have transverse slots 48 therein. The bottom walls of the book holders also have transverse slots 49 therein. The flanges B' have transverse slots 49' therein, and a coupling pin 50 projects through these slots 48, 49 and 49' and through the latch arm 44. The slots 49 and 49' are parallel and the slot 48 is at an angle to the slots 49 and 49' in each assemblage, so that when the arm 44 causes the coupling pin 50 to move in the slots it exerts a certain amount of cam action against the walls of the slots to cause the angle plate 43 and lip 41 and also the arm 44 to move forwardly or rearwardly, as the case may be; the forward movement of the lip, of course, releases the book and the rearward movement insures the coupling engagement of the book and the book holder.

The angularly-shaped flange or support at the front of the cabinet is provided with openings 51 therein, through which the finger of the hand may be inserted to operate a loose-leaf binder. When the book is released from the book holder and it is desired to change the pages in the book, it may be moved forward and rest upon the flange or support 5 and be completely opened to break the binder of the loose-leaf book, if it be that type of book.

Referring to Figures 5, 7 and 8 of the drawings, a clear space is shown between the angular flange 5 and the upper edge of the front wall 2' of the cabinet. Figure 7 shows the book in the open position and the finger grip 47 in position below the lower edge of flange 5 where it can be readily manipulated. Referring to Figure 9, the fourth holder from the left shows the finger grip 47 in the normally closed position and the holder is free to swing without interference from flange 5. When the finger grip 47 is moved to the left to release the book from the holder, as is shown in the first three holders illustrated in Figure 9, the latch arm 44 is projected outward and the finger grip 47 moves to a posi-

tion under the flange 5, which interferes with the swing of the holder and retains the same in a "locked" relation. This is important to maintain the holder B in a firm position while the book is being removed and manipulated or replaced in the holder.

The operation of the mechanism is as follows, particular reference being made to Figures 5, 6, 7 and 8 of the drawings:

- 10 Figures 5 and 6 show the position of the book holders and books when in closed position, Figure 5 showing the closure 29 elevated and holding the books in the cabinet, and also preventing loss or injury from fire or theft or the entrance of dust and dirt into the cabinet. Before operating any of the books it is, of course, necessary first to lower the closure 29. It will be noted that when the books are in closed position the link 9
15 has its pivotal connection 10 with the book holder B at a point above the rod 7, which constitutes the pivot of the book holder, and the pivot 23 of the link 22 is forward of the rod 7 but substantially in line therewith.
20 25 To swing the book from closed to open position, the operator grasps the rear end or furthest end of the book holder and exerts an upward and forward pull thereon. This causes the book holder B to swing on its rod
30 or pivot 7 and causes the pivot 10 to swing in an arc from a point above the rod 7 to a point below the rod 7, as indicated in Figure 7.

During this movement of the link 9 the lever 35 13 is forced downwardly and rearwardly, assisted by the contraction of the spring 17. The spring 17 exerts its greatest force at the beginning of the movement and its force diminishes and is completely dormant as the 40 parts reach the end of the movement. As the book swings from closed to open position the link 22 through the medium of the plate or bell crank lever 24 causes the dash pot 26 to function, and this function resists the tendency of the book to fall, counterbalancing the 45 weight thereof, and causing or permitting the same to slowly move to its completely open position.

When the book and book holder are moved 50 from open to closed position the action of the linkage is reversed. During the beginning of this motion or movement the spring 17 offers practically no resistance whatever. However, as this movement continues the 55 spring is expanded and continues to be expanded, offering increasing resistance to the fall of the book holder. As the book holder and book near the extremes of both movements, they are prevented from banging or 60 striking the walls of the cabinet with any appreciable force by the action of the dash pot 26, but it is understood that this dash pot is regulated so that its operation does not hinder the normal movement of the parts, but 65 prevents bangs and jars which would occur

if the book holders were thrown with force on their pivots.

Due to the fact that the book holders are pivoted on the rod in such a way that the pivots are nearer one end of the book holders than the other, the force of gravity is utilized to cause the complete opening and closing movements of the books and book holders, such movement, as above stated, being resisted to the desired extent by the operation of the dash pot.

A device of this character lends itself to a wide range of utility and handling of any type of book. A single book can be opened and can rest in convenient position for entries or for examination, as clearly shown in Figure 2 of the drawings, or any or all of the books may be swung to open position and quick reference made to the different books. This idea is illustrated in Figure 3 of the drawings.

It will be noted particularly by reference to Figures 5, 7 and 8 of the drawings that I provide cushions 52 and 53, which act to prevent any bang or noise and relieve jars in the manipulation of the books and book holders. When the book is open the end of the book holder rests upon the cushion 52, and when the book is in closed position the book bears against the cushion 53.

To further assist in preventing the admission of dust and dirt to the interior of the cabinet, I may provide on the end of each book holder B a tongue 54 which has a slightly curved free end so that when the book holder is in closed position this tongue will project under the cushioned upper end of the front walled section 2', as clearly indicated in Figure 5 of the drawing.

While I have illustrated what I believe to be the preferred embodiment of my invention, it is obvious that various changes may be made in the general form and arrangement of the parts without departing from the spirit of the invention; hence I do not limit myself to the specific details set forth but consider myself at liberty to make such changes and alterations as fairly fall within the scope of the claims.

What is claimed is:

1. In a bookrack, the combination with a support, of a book holder pivotally mounted on the support and adapted to support a book normally in suspended closed position, and adapted to be swung on its pivot to a reverse position to support the book and permit opening thereof, automatic and progressively variable counterbalancing tension means pivotally connected to one side of the book holder, and movement cushioning means pivotally connected to the other side of the book holder.

2. In a bookrack, the combination with a support, of a book holder pivotally mounted on the support and adapted to support a book normally in suspended closed position, and

- adapted to be swung on its pivot to a reverse position to support the book and permit opening thereof, counterbalancing means operatively connected to one side of the book holder, movement cushioning means operatively connected to the other side of the book holder, said cushioning means including a dash pot, and a link operatively connected to the dash pot.
- 10 3. In a bookrack, the combination with a support of a book holder pivotally mounted on the support and adapted to support a book normally in suspended closed position, and adapted to be swung on its pivot to a reverse position to support the book and permit opening thereof, counterbalancing means operatively connected to one side of the book holder, movement cushioning means operatively connected to the other side of the book holder, said cushioning means including a dash pot, and a link operatively connected to the dash pot, said link being pivotally connected to the book holder at a point removed from the pivotally mounting of the book holder, whereby said link pivot swings from one side to the other of the book holder pivot during the movement of the book holder.
- 15 4. In a bookrack, the combination with a support, of a book holder pivotally mounted on the support and adapted to support a book normally in suspended closed position, and adapted to be swung on its pivot to a reverse position to support the book and permit opening thereof, counterbalancing means operatively connected to one side of the book holder, and movement cushioning means operatively connected to the other side of the book holder, said counterbalancing means including a link pivotally connected to the book holder at a point above the book holder pivot, said link pivot being movable to a point below the book holder pivot when the book holder is swung from one extreme position to the other.
- 20 5. In a bookrack, the combination with a support, of a book holder pivotally mounted on the support and adapted to support a book normally in suspended closed position, and adapted to be swung on its pivot to a reverse position to support the book and permit opening thereof, counterbalancing means operatively connected to one side of the book holder, movement cushioning means operatively connected to the other side of the book holder, said counterbalancing means including a link pivotally connected to the book holder at a point above the book holder pivot, said link pivot being movable to a point below the book holder pivot when the book holder is swung from one extreme position to the other, a lever pivoted to the support and to which one end of said link is connected, and a spring connecting the lever to the support and resisting the movement of the lever in one direction and assisting the

movement of the lever in the opposite direction.

6. A bookrack including a support, a book holder pivotally mounted between its ends in the support, an arm pivotally mounted in the support, a link pivotally connecting the book holder and the arm, and a coil spring connecting the arm to the support whereby said link, lever and spring constitute counterbalancing means for the book holder.

7. A bookrack including a support, a book holder pivotally mounted between its ends in the support, a lever pivotally mounted in the support, a link pivotally connecting the book holder and the lever, an arm pivotally connected to the lever, an adjusting screw operatively connected to the arm and carried by the lever, whereby the angular disposition of the arm may be varied, and a cushioning spring connecting the free end of the arm with the fixed part of the support.

8. A bookrack including a cabinet, a rod extending through the upper portion of the cabinet, a plurality of book holders pivotally supported on the rod and adapted to support books which are suspended therefrom when the books are in closed position within the cabinet, independent automatic and progressively variable counterbalancing tension means for each book holder operatively connected to the book holders and located within the cabinet, said book holders and books located at an angle to the perpendicular, and the outer faces of the book holders substantially flush with the top of the cabinet, whereby a surface is provided for the support of a book at an angle to the perpendicular when the books are moved to open position.

9. A bookrack including a cabinet, a rod extending through the upper portion of the cabinet, a plurality of book holders pivotally supported on the rod and adapted to support books which are suspended therefrom when the books are in closed position within the cabinet, independent variable counterbalancing means for each book holder operatively connected to the book holders and located within the cabinet, said book holders and books located at an angle to the perpendicular, the outer faces of the book holders substantially flush with the top of the cabinet, whereby a surface is provided for the support of a book at an angle to the perpendicular when the books are moved to open position.

10. A bookrack including a cabinet, a rod extending through the upper portion of the cabinet, a plurality of book holders pivotally supported on the rod and adapted to support books which are suspended therefrom when the books are in closed position within the cabinet, independent variable counterbalancing means for each book holder operatively connected to the book holders and located within the cabinet, said book holders and books located at an angle to the perpendicular, the outer faces of the book holders substantially flush with the top of the cabinet, whereby a surface is provided for the support of a book at an angle to the perpendicular when the books are moved to open position, a closure having sliding mounting on the back of the cabinet, and a hinged section on the said closure adapted to be connected to the top of the cabinet to cover the ends of the book holders and books when the latter are not desired for use.

11. A bookrack including a book holder pivotally mounted in the rack, a fixed book-engaging lip at one end of the holder, a movable book-engaging lip at the other end of the holder, and a laterally swinging member

having slot and pin connection with the movable book-engaging lip for causing movement of the movable book-engaging lip.

11. A bookrack including a book holder 5 pivotally mounted in the rack, a fixed book-engaging lip at one end of the holder, a movable book-engaging lip at the other end of the holder, a laterally swinging member operatively connected to the movable book- 10 engaging lip, a movable plate within the book holder, said plate and the wall of said book holder having slots at an angle to each other, and a pin carried by the laterally swinging member movable in said slots and exerting a 15 cam action on the plate to move the movable book-engaging lip.

12. A bookrack including a support, a book holder pivotally mounted between its ends in the support, a link connected to the book 20 holder, a dash pot pivotally mounted in the support, and a member pivotally connected to the support and connecting the link and dash pot.

13. The combination with a book stand, the 25 front wall of which is set back permitting leg spacing and providing support for the closed books, a rod projecting through the upper portion of the cabinet, a plurality of book holders pivotally supported on the rod, and 30 adapted to support books normally suspended therefrom and confined within the cabinet, any or all of said book holders and books adapted to swing on their pivots and permit the books to open and be supported on the top 35 of the cabinet, an independent automatic and progressively variable counterbalancing tension and cushioning means operatively connected to each book holder.

14. The combination with a support, a 40 front wall of the support having a clear space near its end therein, a book holder pivotally mounted in the support, book securing means for coupling the book holder to the book, said means including an arm having a lateral as 45 well as a longitudinal movement to operate the coupling means, said arm being projected forwardly so as to project into said clear space and be held by the upper wall of said clear space to prevent turning movement of the 50 holder when a book is uncoupled from the holder.

15. The combination with a support, a hollow book holder pivotally mounted in the support, an angle plate movably mounted in one 55 end of the holder and having a book-engaging member at one end, a flange on the book holder located parallel to the upper member of the angle plate and spaced therefrom, an arm extending longitudinally of the book 60 holder, and having a longitudinal movable and fulcruming mount in the vertical portion of said angle plate, the wall of said book holder and said flange having normally parallel slots therein at an angle to the slot in the 65 angle plate, and a pin projected through the

slots of all of said members so that when the arm is pivotally swung from one side to the other the angle plate of the book securing member is moved longitudinally of the book holder.

16. The combination with a support, a hollow book holder pivotally mounted in the support, an angle plate movably mounted in one end of the holder and having a book engaging member at one end, a flange on the book holder located parallel to the upper member of the angle plate and spaced therefrom, an arm extending longitudinally of the book holder, and having a longitudinal movable and fulcruming mount in the vertical portion of said angle plate, the wall of said book holder and said flange having normally parallel slots therein at an angle to the slot in the angle plate, a pin projected through the slots of all of said members so that when the arm is pivotally swung from one side to the other the angle plate of the book securing member is moved longitudinally of the book holder, and a member constituting a part of the support and under which the forward end of the arm is projected when the book engaging member is in releasing position whereby the book holder is held against pivotal movement.

17. The combination with a support, of a book holder pivotally attached to the support, means for securing a book to the holder, said means including a movable book-engaging member at one end of the holder and a member adapted to move the said movable book-engaging member and which when in its book-releasing position is projected under a portion of the support to prevent pivotal movement of the book holder.

Signed at Long Island City in the county 105 of Queens and State of New York this 9th day of June A. D. 1930.

WALTER E. HASKIN.
